UNITED STATES PATENT OFFICE.

CHARLES E. SCRIBNER, OF CHICAGO, ILLINOIS, ASSIGNOR TO THE WESTERN ELECTRIC COMPANY, OF CHICAGO, ILLINOIS, A CORPORATION OF ILLINOIS.

TELEPHONE-EXCHANGE SYSTEM.

SPECIFICATION forming part of Letters Patent No. 772,833, dated October 18, 1904.

Application filed October 21, 1899. Serial No. 734,355. (No model.)

To all whom it may concern:

Be it known that I, CHARLES E. SCRIBNER, a citizen of the United States, residing at Chicago, in the county of Cook and State of Illinois, have invented a certain new and useful Improvement in Telephone-Exchange Systems, of which the following is a full, clear, concise, and exact description.

My invention applies to telephone-exchange systems in which call-signals are transmitted to the operator at the switchboard from the substations automatically in the use of the substation-telephones, the switchboard-signals being subsidiary signaling instruments controlled through the medium of relays responsive to currents in the lines. In switchboards provided with this type of signals hitherto constructed the signal-controlling relay has been placed in a branch or bridge of the line-circuit, together with a source of current, and the plug-circuits for uniting lines have been interrupted as to continuous currents by interposed repeating-coils in order that the relays might be permitted to respond independently each to current in its own line only. This arrangement has been open to the objection that the relay was shunted by the repeating-coil to the extent under some circumstances of rendering it inoperative. My present improvement upon this system consists in constructing the relay in the line-circuit to serve itself as a repeating-coil and in adapting the circuits within the switchboard to this change in the apparatus. By this reorganization of the system the entire signaling-current through the line is caused to traverse the line-relays under all circumstances, and the independent working of the relays is obtained without the use of supplemental apparatus in the plug-circuit, so that both an improved mode of operation and an economy of apparatus are attained. The conductive independence of the portion of the line extending to the substation from the portion leading into the switchboard has the further advantage that no variation of the current in the line is produced in the act of switching the line, the switch connections being independent and lo-

cal, whereby annoying clicks and disturbances in the telephones of calling subscribers are avoided. This improved system, then, involves a repeating-coil provided with an armature having switch-contacts for controlling the circuits through the subsidiary signals. The telephone-line is closed through one helix of this repeating-coil, a battery or other source of current being looped into the circuit, preferably at the middle of the resistance in the repeating-coil helix. The other winding of the repeating-coil is led to the spring-jacks or connection - sockets in the switchboard. When a connection is completed between two lines by means of a plug-circuit, the two lines are united inductively through the medium of their respective repeating-coils, the circuit through the switchboard being a local circuit with no conductive connection with the line-circuits and free from battery connections. Thus each of the line-helices of the repeating-coils controls its own armature in response to currents through its own line determined by the use or disuse of the corresponding telephone.

My improvement is shown in the accompanying drawing in connection with a system of subsidiary signals which forms the subject of a prior patent, No. 669,708, dated March 12, 1901.

In the drawing, two telephone-lines are represented terminating in a telephone-switchboard. Line conductors 1 and 2 of the line are permanently united at the substation through a conductor 3, which includes a polarized signal-bell a and which is interrupted as to unvarying currents by the condenser a' interposed in it. A second bridge, 4, of the line includes the usual receiving-telephone a^2 and transmitting - telephone a^3 and is normally open at the switch-contacts of a telephone-switch a^4 . The telephones may be provided with any of the well-known means of supplying current for the operation of the transmitting instrument.

At the central station the line conductors 1 and 2 are united through the winding b' of the repeating-coil b and through the battery

c. In other words, the line conductor 1 may be considered as extending through one half the winding b' to one pole of battery c and the line conductor 2 through the other half of the same winding to the other pole of battery c . This battery may be common to the different telephone-lines of the exchange. The other helix, b^2 , of the repeating-coil is connected by wires 5 and 6 with the line-contacts of spring-jacks d and d' in the switchboard.

The core of the repeating-coil b is provided with an armature b^3 , whose lever closes upon a contact-point b^4 when it is attracted. The lever-carrying armature b^3 is connected by a conductor 7 with one pole of battery c , while the contact-point b^4 of the relay is connected by a conductor 8 with the other pole of the battery. A resistance-coil e is interposed in conductor 7. A signal-lamp f is included in conductor 8, placed near the spring-jack d' in the switchboard, so as to be permanently associated with it. Conductor 7 is also connected with the contact-rings g^2 of the spring-jacks by a wire 9, brought from a point between the resistance-coil and the lever of the relay.

Two plugs h and h' , forming the terminals of a plug-circuit 10 11, are shown at one section of the switchboard. In addition to the usual contact-pieces i and i' , which register with the line-springs g and g' of the spring-jack, there is a sleeve i^2 in the plug which connects with the thimble g^2 of the spring-jack. The two sleeves i^2 of the plugs h and h' form the terminals of two wires 12 and 13, respectively, which include supervisory signal-lamps k and k' , associated with the corresponding plugs. These conductors are united and connected through a wire 14 with a battery c . The usual calling-key l is furnished for the use of the operator in signaling to a substation and a listening-key m for connecting her telephone with the plug-circuit. This system of circuits comprises two distinct organizations, both supplied with exciting-current from battery c . One system consists of the line-circuit including one helix of the relay b and controlled at the substation, the design being to cause the excitement of the relay during the use of the substation-telephone, the secondary circuit including the other helix of the repeating-coil and terminating in the spring-jacks in the telephone-switchboard and the line-contacts of the plugs and the conductors which unite them for establishing connections between the secondary circuits of different lines. The other system consists of local circuit connections controlled by the relay for causing the illumination of the line-lamp in response to the excitement of the relay as an initial signal, for extinguishing the line-lamp when connection is made with the line, for temporarily substituting for the line-lamp a supervisory signal-lamp, and for causing the illumination of this latter lamp when the tele-

phone is returned to its position of disuse. This latter system of circuits forms no part of the present invention, but is made the subject of the prior patent mentioned.

As long as the telephone at the substation—station A, for example—is not in use no current circulates in the line conductors 1 2, since the connection between these is interrupted at the substation by the condenser a' and the switch a^4 . When the telephone is removed from its switch for use, the switch closes the bridge 4, which is of comparatively low resistance, whereupon a current is created by battery c in the line which magnetizes the core of relay b and causes the attraction of armature b^3 . The local circuit of battery c is thus closed through conductors 7 8. The current in this circuit illuminates the lamp f , whereby the initial call is signalized to the attendant. In response to this signal the operator inserts the plug h into the spring-jack d' and depresses the key m , thus bringing her telephone into a closed circuit with the helix b^2 of coil b , so that she can learn the order for the required connection. A new arrangement of the local circuits is at the same time brought about, a path being formed from battery c through wires 14 and 12 to the sleeve i^2 of the plug, thence to the thimble g^2 of the spring-jack, and thence through wires 9 and 7, returning to battery c . The supervisory lamp k is thus brought into parallel circuit with the line-lamp f , both being in series with the resistance-coil e . This coil is of such resistance with relation to that of the lamps that the current through it is insufficient to illuminate both lamps when thus placed in parallel. Consequently the line-lamp f is extinguished and the supervisory lamp k remains unlighted.

When the number of the desired correspondent line B has been obtained, the operator may test the spring-jack of that line in the usual way and, finding the line free, may insert the plug h' into the spring-jack. She may then signal the required station B by means of the calling-key l . While the line-circuit at that station remains discontinuous, the relay b of the line remains inert, so that the circuit through the line-lamp f , which it controls, is open. Hence the entire current through wire 7 and resistance-coil e of that line traverses the path 9, 13, and 14, lighting the supervisory lamp k' . The illumination of this lamp then indicates to the operator that the called subscriber has not responded.

When the telephone at the station B is removed from its hook, the repeating-coil relay becomes excited and closes the circuit through its lamp f , thus extinguishing the supervisory lamp k' . The two lines will then be in inductive connection with each other. Telephonic currents through line-circuit 1 2 to station A will be repeated by the coil b in that line into the secondary circuit, made up of conductors 5 6 of each of the lines, and the

plug-circuit 10 11, and from this secondary circuit again into the line-circuit through the medium of the repeating-coil *b* in the line to station B.

5 While the telephones at the substations remain in use the supervisory lamps will remain dark; but when both telephones are replaced upon their switch-hooks both relays will release their armatures, whereby the currents 10 through both line-lamps *f* will be interrupted, and the entire currents through the coils *e* will be diverted through the supervisory lamps *k* and *k'*, respectively. The simultaneous illumination of these lamps may be taken as a 15 signal for disconnection.

It will be apparent that no action of the operator in making or breaking connection between lines can vary the current in the line-circuits, the latter being dependent wholly on 20 the position of the telephone-switches at the stations. Hence no disturbance can arise in the telephones through changes in the strength of current in the line resulting from altering the circuit connections in the switchboard 25 such as characterize the systems for automatic signaling commonly in use.

I claim as my invention—

1. The combination with a telephone-circuit and means for producing signaling-current in 30 the circuit, of a repeating-coil interposed in the circuit, an armature for the repeating-coil responsive to the flow of signaling-current therein, a local circuit containing a subsidiary signal and a source of current, switch-35 contacts operated by the armature of the repeating-coil, controlling said local circuit, a second subsidiary signal in a conductor adapted to form a shunt about the first-mentioned signal and the switch-contacts, and means for 40 closing said shunt-path, whereby both of said subsidiary signals are rendered responsive at different times, to the flow of signaling-current in the main telephone-circuit, substantially as set forth.

45 2. The combination with a telephone-line extending from a substation to a central office, of a spring-jack for the line at the central office, a repeating-coil interposed between the spring-jack and the line, one winding of said 50 repeating-coil being in the line-circuit and the other winding in the portion of the circuit leading to the spring-jack, a source of signaling-current in the main circuit with a switch at the substation for determining the flow of 55 current in the line, a plug and plug-circuit for making connection with the line at the spring-jack thereof, an armature for the repeating-coil, a subsidiary line-signal in a local circuit, switch-contacts operated by the ar- 60 mature controlling said local circuit, a shunt- 65 circuit about said line-signal, said shunt-circuit being established in making connection with the line, and a supervisory signal in the shunt-circuit, as described.

65 3. The combination with a telephone-line

having a battery permanently connected in its circuit at a central office, and a switch at the substation controlling the circuit, of a signal-controlling magnet having a winding in the circuit, the signal being responsive to the 70 movements of the substation-telephone switch, a second winding for said electromagnet in inductive relation to the first-mentioned winding, a telephone-circuit and a switch for bringing said circuit into connection with the second winding of the magnet, whereby said circuits are united inductively.

4. In a telephone-exchange system, the combination with two lines extending from substations to a central office, of a repeating-coil 80 for each line at the central office, having one of its windings in the line, means for temporarily connecting together the remaining windings of the coils, to unite the two lines telephonically, a source of current permanently connected with each line, and a switch at each substation controlling the circuit, a relay-armature for the core of each coil, a line-signal for each line in a local circuit controlled by the relay-armature of the corresponding repeating-coil, a supervisory signal for each line, 85 and a local circuit for each of said supervisory signals bringing the same under the control of the corresponding relay-armature, established in connecting the two lines telephonically through their repeating-coils, substantially as set forth.

5. In combination, two telephone-lines, each having a switch at its substation for closing the line, a source of current in each line, a repeating-coil for each line having one winding in the line-circuit, an armature for the core of each repeating-coil, a subsidiary line-signal for each line in a local circuit controlled by the armature of the corresponding repeating-coil relay, means for uniting the remaining windings of the two repeating-coils, two subsidiary supervisory signals, and means for temporarily associating each of the signals with one of the said local circuits to be controlled by the said repeating-coil relay, when connection is made between the said windings, substantially as described.

6. In combination, two telephone-lines, each having at its substation a telephone-switch for closing the line-circuit, a source of current in each line-circuit, a repeating-coil for each line having one of its windings in the line-circuit, and having its other winding connected with a spring-jack in a switchboard, an armature controlled by the core of each repeating-coil, a subsidiary line-signal in a local circuit with a source of current controlled by the armature of the corresponding repeating-coil, a plug-circuit for uniting different spring-jacks, a supervisory signal associated with each plug and circuit connections closed in the act of putting a plug into a spring-jack adapted to bring the corresponding supervisory signal into a circuit controlled by the relay of the

line with which the plug is connected and to shunt the line-signal, substantially as described.

7. The combination with a telephone-line, 5 a battery permanently connected with the line at the central office, a switch determining the flow of current in the line operated in the use of the telephone, and a repeating-coil interposed in the line-circuit, of relay-contacts controlled by the repeating-coil, a socket for the line and a plug and plug-circuit therefor, a supervisory signal associated with the plug-circuit, and circuit connections closed in making connection with the line adapted to bring 15 the signal under the control of the repeating-coil relay, the supervisory signal being thereafter responsive to the movements of the relay-armature produced by the flow of signaling-current in the line, as described.
- 20 8. In a central-battery telephone system, the combination with telephone-lines extending from substations and permanently connected at the central office to the poles of a central battery, of a substation-telephone switch for 25 each line controlling the flow of current therein, a repeating-coil magnet for each line having a winding connected in the line-circuit and an independent winding in inductive relation to said first-mentioned winding, link 30 conductors at the central office, and connection-switches adapted to establish a local circuit through said link conductors including the independent windings of the magnets of two lines, whereby the said two lines are 35 united telephonically, an armature for the repeating-coil magnet of each line, and signal apparatus responsive to the movements of said armature to indicate the open or closed condition of the telephone-switch at the corresponding substation, substantially as set forth.
- 40 9. In combination, two telephone-lines extending from substations to a central office, a battery permanently connected with both lines, and a switch at the substation of each 45 line for controlling the flow of current there-

in, a repeating induction-coil for each line having one of its windings included directly in the line-circuit, an armature for each repeating-coil controlling a local circuit containing a subsidiary signal, and means for switching the remaining windings of the repeating-coils together, to form an intermediate switchboard-circuit, and to constitute a talking-circuit composed of three inductively-united sections between the substations of said lines, 55 the said talking-circuit having a source of steady current in each of its two end or line sections, but not in the central or switchboard section, the signals controlled by the battery-current being responsive independently each 60 to current in its own line, substantially as set forth.

10. The combination with a telephone-line extending from a substation to a central office, 65 of a source of current and means at the substation for determining the flow of current in the line, a repeating-coil at the central office having one winding included in the line-circuit and another winding independent thereof, a spring-jack for the line, a plug for making connection therewith, and a switchboard-circuit, established in registering contacts of the plug and spring-jack, including the second-mentioned winding of the repeating-coil, 70 an armature for the repeating-coil, a local circuit including a subsidiary line-signal controlled by said armature, the line-signal being responsive to the movement of said armature, a supervisory signal and a circuit including the same, established in making connection with the spring-jack of the telephone-line, said last-mentioned circuit being in shunt 75 of the subsidiary line-signal, as described.

In witness whereof I hereunto subscribe my name this 2d day of October, A. D. 1899. 85

CHARLES E. SCRIBNER.
